UNITED STATES PATENT OFFICE.

WILLIAM B. ROOD, OF WARE, MASSACHUSETTS, ASSIGNOR TO OTIS COMPANY, OF WARE,
MASSACHUSETTS, A CORPORATION OF MASSACHUSETTS.

UNDERGARMENT.

Specification of Letters Patent. Patented July 11, 1916.

1,190,590.

Application filed September 30, 1915. Serial No. 53,358.

To all whom it may concern:

Be it known that I, WILLIAM B. Rood, a citizen of the United States, residing at Ware, county of Hampshire, State of Massachusetts, have invented a certain new and useful Improvement in Undergarments, of which the following is a specification, reference being had therein to the accompanying drawings.

10 My invention relates to a new and improved union undergarment.

The particular object of the invention is to produce an undergarment which shall have great elasticity lengthwise of the back thereby permitting free movement and at the same time shall not sag or bag at the seat, shall be strong and be capable of resisting any strain which may be placed upon the garment without doing injury to the 20 fabric composing the garment.

My invention is applicable equally to garments made from woven fabric such as nainsook as well as to garments made of knit goods, when it is desirable to give greater elasticity lengthwise of the back of the garment than is possessed by the goods of which it is made.

Undergarments both of knit and woven materials have been made with an elastic 30 insert of knit material in the small of the back, the wale of the insert running horizontally. As is well known to those skilled in the art, certain kinds of knit material are very elastic transversely of the wale if 35 they are not stretched in this direction beyond a certain limit, but that, if sufficient strain is put upon the fabric to elongate it beyond this limit, a permanent elongation is produced so that the knit fabric thereaf- 40 ter lacks the power of returning to its original condition. In garments such as previously described, it has been found that the wearer stretches the elastic insert at the waist to the point where a permanent elongation takes place, and that thereafter the garment tends to sag through the seat. My present invention therefore has for its object 45 to provide a garment which while having

all the advantages afforded by the elasticity of the knit elastic insert at the waist shall not be liable to sag at the seat owing to a permanent elongation of the knit insert at the waist.

The invention will be fully understood from the following description when taken in connection with the accompanying drawings and the novel features thereof will be pointed out and clearly defined in the claims at the close of this specification.

Referring to the drawings, Figure 1 is a back view of a knit garment embodying my invention. Fig. 2 is a section on line 2-2 of Fig. 1. Fig. 3 is a view of the elastic reinforcement of the back of the garment showing the condition of the parts when the elastic reinforcement is stretched to the limit. Fig. 4 is a section on line 4-4 of Fig. 3. Fig. 5 is a view of the material for the body of a union garment such as is shown in Fig. 1, said material being laid out flat, the figure showing particularly the slit for the elastic insert. Fig. 6 is a view similar to Fig. 1 of a nainsook garment showing a modified form of my invention. Fig. 7 is a section on line 7-7 of Fig. 6. Fig. 8 shows another modification of my invention. Fig. 9 is a section on line 9-9 of Fig. 8.

Referring now to the drawings at 11 is shown the shirt portion, and at 12 the drawers portion of the union undergarment. In ordinary practice these portions of the garment are made of nainsook or of knit goods with the wale of the cloth running vertically so that the garment is relatively inelastic to any strain which tends to stretch the garment lengthwise of the back, as is the case when the wearer is bending over or stooping down.

At 13 is shown a substantially horizontal elastic insert extending from side to side of the back of the garment at about the waist line. This insert is made of elastic knit goods with the wale running horizontally and gives elasticity to the garment when the wearer bends over or stoops down. The elastic insert is preferably widest at its cen-

tral part at the middle of the back of the garment, tapering thence both ways toward the sides of the garment, and is also preferably two-ply or of double thickness as shown at 13, 13 of Fig. 2, but it is not necessary that both layers of the elastic fabric shall extend the entire distance from side to side of the back of the garment. Other forms are hereinafter referred to. By having the insert of double thickness, the power of the fabric to return to its original condition is materially increased.

The two thicknesses of knit goods which form the elastic insert 13 are secured to the shirt and drawers portion of the garment by the seams *a* and *b*. When the garment is made of tubular knit fabric, as is the case in Fig. 1, I make a horizontal slit at the waist line as shown at 31 in Fig. 5, and setting 15 away any of the material of which the body of the garment is constructed. This gives additional fullness at the seat of the garment and produces a more comfortable, 20 durable and better fitting garment.

Between the two layers 13, 13 of the elastic insert and about centrally thereof I place a piece of tape 15 or other strong in- 25 elastic fabric and secure the upper end to the shirt portion of the garment by the seam *a* and the lower end to the drawers portion by the seam *b*. For convenience I call this member 15 a concealed stay, and its length is slightly less than the vertical 30 width of the elastic insert 13 when it is stretched to a distance slightly less than that at which permanent elongation or distortion of the fabric seems to begin. The position of the parts, when the elastic material 35 13 is not under tension, is clearly seen in Figs. 1 and 2. At this time the tape is loose or slack and lies in superposed or adjoining folds. The position of the parts, when the garment is subjected to heavy ver- 40 tical strain, is shown in Figs. 3 and 4. It will be seen that the elastic insert 13 permits the garment to be stretched lengthwise of the back to a considerable extent and the concealed stay 15 takes the strain just before the point at which permanent elongation 45 is produced is reached. The stay also serves to prevent any rupture of the fabric.

The garment thus constructed may be made exceedingly flexible and elastic but 50 will maintain its shape much better than similar garments as heretofore constructed. The durability of the garment is also much increased. It will be also seen that the concealed stay is not exposed to view and is 55 protected so that it cannot catch on anything nor can the wearer catch his fingers in it in putting on or taking off the garment. The concealed stay is ordinarily 60 made of cotton tape which is so thin and

light that although giving sufficient strength 65 to the garment it does not bunch up and its presence will never be perceived by the ordinary wearer, unless something calls his attention particularly to it.

In Figs. 6 and 7 I have shown my invention in slightly modified form. In this form the outer layer of fabric is designated 16, the inner layer 17 and the concealed stay 18. It will be seen that the inner layer 17 of fabric forming in part the elastic insert is 75 relatively short, but is long enough to increase materially the power of the insert to return it to its original position and protect and conceal the stay 18.

In Figs. 8 and 9 is still another form of my invention. In this form the elastic insert at the waist is formed by two overlapping members 21 and 22, said members being of substantially the same size and shape and having their ends overlapping at the 85 middle of the back. The concealed stay 23 is placed between the overlapping ends of the two portions 21 and 22.

In all of the forms of the invention the concealed stay takes the strain just before 90 the point is reached at which the elastic insert will be likely to receive a permanent elongation.

What I claim is:

1. A union undergarment having its shirt 95 and drawers portions made of relatively inelastic material when stretched lengthwise of the back, an elastic insert at the back of the garment at the waist, and a normally slack, non-elastic stay of greater length than 100 the width of said insert, said stay spanning said elastic insert and having its ends secured respectively to the shirt and drawers portions of the garment.

2. A union undergarment having its shirt 105 and drawers portions made of relatively inelastic material when stretched lengthwise of the back, an elastic two-ply insert at the back of the garment at the waist, said insert being widest at its central portion at 110 the back of the garment and tapering thence toward the sides of the garment, and a normally slack, non-elastic stay spanning said elastic insert at its middle portion and having its ends secured respectively to the shirt 115 and drawers portions of the garment.

3. A union undergarment having its shirt and drawers portions made of relatively inelastic material when stretched lengthwise of the back, an elastic insert at the back of 120 the garment at the waist, said elastic insert being of double thickness at the small of the back, and a concealed, normally slack, non-elastic stay between the two thicknesses of said elastic insert and having its ends secured respectively to the shirt and drawers 125 portions of the garment.

4. A union undergarment having its shirt

and drawers portions made of a single piece of relatively inelastic material when stretched lengthwise of the back, an elastic two-ply insert at the back of the garment at the waist, said insert being widest at its central part, tapering thence toward the sides of the garment, and a normally slack non-elastic stay disposed between the two plies of said elastic insert and having its ends se-

cured respectively to the shirt and drawers 11 portions of the garment.

In testimony whereof I affix my signature, in presence of two witnesses.

WILLIAM B. ROOD.
